(57) CLAIM

The ornamental design for a dispensing bottle, as shown and described.

DESCRIPTION

FIG. 1 is a front elevational view of a dispensing bottle showing my new design, the opposite side is a mirror image thereof;

FIG. 2 is a side elevational view at 90 degrees to FIG. 1, the opposite side is a mirror image thereof;

FIG. 3 is a top view of the dispensing bottle of FIG. 1; and,
FIG. 4 is a bottom view of the dispensing bottle of FIG. 1.
The broken lines in the drawings are included for the purpose of illustration and form no part of the claimed design.
